UNITED STATES PATENT OFFICE.

GEORGE H. FORSYTH, OF CHICAGO, ILLINOIS.

DRAW-BAR GUIDING AND RESISTANCE MECHANISM.

SPECIFICATION forming part of Letters Patent No. 772,653, dated October 18, 1904.

Application filed February 27, 1904. Serial No. 195,616. (No model.)

To all whom it may concern:

Be it known that I, GEORGE H. FORSYTH, a citizen of the United States, residing at Chicago, in the county of Cook and State of Illinois, have invented certain new and useful Improvements in Draw-Bar Guiding and Resistance Mechanism, of which the following is a specification.

This invention relates to a device for preventing injurious side thrust on a draw-bar capable of angular or lateral movement during buffing or coupling.

Heretofore the practice in railway-car construction has been to limit more or less the lateral movement of the free end of the draw-bar, so that the latter would remain substantially upon the median line of the car, the result of this construction being that when the draw-bars met at an angle in coupling, as on a curve, or received a substantial buff the lateral strain at the limiting points was more or less injurious and undesirable. More recently it has been the practice to increase this limit of movement for the free or coupling end of the draw-bar for curves or during lateral movement thereof under strain, whether on curves or straight track, until the draw-bars are allowed to assume a position coincident with the line of draft, which it is their natural tendency to do. During buffing or coupling, however, which causes a lateral movement of the draw-bars, there is a sudden side thrust due to this increase in the limit of movement, with disastrous and damaging results by reason of the draw-bars being thrust violently against their lateral-movement limits without restraint, tending to break the interlocking parts of the coupling-head.

It is the object of the present invention to overcome these difficulties and to provide a construction which will permit the necessary lateral movement of the draw-bars in order to bring them in line with the line of draft, but at the same time will prevent a violent or sudden side thrust during buffing or coupling, with its consequent injury to the draw-bars and coupling-heads; to provide a construction by means of which an additional resistance medium is thrown into operation dur-

ing buffing or coupling, and to provide a construction tending to return the draw-bar to a central or normal position.

The invention will be readily understood from the following description, reference 55 being had to the accompanying drawings, in which—

Figure 1 is a plan view of the invention with parts broken away as applied to the ends of cars shown in fragment. Fig. 2 is an end view of the same. Fig. 3 is a plan view of a modified form. Fig. 4 is a plan view of a further-modified form of the invention with parts broken away. Fig. 5 is an end view of the invention shown in Fig. 4. Fig. 6 is a 65 plan view of still another form embodying the invention, and Fig. 7 is an end view of the invention as shown in Fig. 6.

Referring to the drawings, 1 and 2 designate, respectively, the ends of cars to which 70 the invention is applied, each being provided with a draw-bar 3 of any desirable pattern and provided with the usual draft-rigging spring 4 to provide for a longitudinal movement of said draw-bar. The free or coupling end of 75 the draw-bar is supported by a carrier-frame 5, which is of sufficient length to allow all necessary lateral movement of the draw-bar thereupon.

6 designates a guide-casing provided with a 80 back plate 7, secured to the end of the car by means of bolts 8 8, said guide-casing being of a hollow or shell-like construction.

9 designates a guide member telescopically mounted within the guide-casing 6 and provided at its sides with pockets 10 to receive coiled expansion-springs 11, by means of which said guide member is capable of a yieldable and extensible movement within said guide-casing, thus permitting said guide member to move 90 outwardly into engagement with the coupler-head of the draw-bar, as well as to permit a longitudinal movement of said draw-bar. The contacting face of the guide member 9 is so formed as to provide inclined surfaces 9' 9' 95 and a central straight surface 9''.

12 designates a horn mounted upon the coupler-head and adapted to engage and move along the contacting face of the guide member 9.

It is obvious from the above that the guide 100

- member 9 by reason of the expansion-springs 11 is moved outwardly until its contacting face engages the horn 12 and also that it moves inwardly and outwardly with the horn 12 during any longitudinal movement of the draw-bar 3, the inclined surfaces of the guide member 9 tending at all times to bring the draw-bar to a central position, if not already so, as well as to retard any lateral movement away from a central position by reason of the fact that the outward tendency of the guide member, with its inclined surfaces tending to obstruct lateral movement of the draw-bar, counteracts any lateral movement of the draw-bar caused by buffing or coupling, thus preventing that sudden side thrust which brings the draw-bar against its lateral-movement limits with a shock which is damaging to the mechanism, and especially the interlocking parts of the coupler-head.
- Fig. 3 shows a modified form of the invention and from which a telescoping guide member is omitted, the guide-casing being provided with a more or less concaved contacting face adapted to engage the horn upon the coupler-head of the draw-bar as the latter moves in and out, said face being provided at its central portion with an inset or socket 13, adapted to receive the horn 14 upon the coupler-head as the draw-bar is retracted during coupling or buffing, it being understood that the draft-bar is capable of an inward movement during buffing or coupling sufficient to bring the horn into engagement with the contacting face of the guide-casing, the inclined surfaces of which tend to swing the horn into the socket 13 or to retard the side thrust from the central position sufficiently to prevent damage to the mechanism or coupler-heads.
- Figs. 4 and 5 show a further modification of the invention and comprise the guide-casing 15, provided with a back plate 16 and secured to the end of the car, as in Fig. 1. Slidably mounted within said guide-casing are two friction-blocks 17, provided with the inclined surfaces 18 and the spring-receiving pockets 19, within which are the coiled expansion-springs 20, moving said friction-blocks toward each other. 21 designates a guide member mounted within the central portion of the guide-casing, which is cut away at the top and bottom, as indicated at 22, and provided with confining-shoulders 23 to prevent same from coming forwardly out of said guide-casing. Said guide member is provided with inclined contacting face-surfaces and a central socket to receive the horn, as in the other constructions, the function of said members being the same as in the other forms or constructions.
- Figs. 6 and 7 present a still further modification of the invention, the guide-casing of which is of different form and made open in front, as indicated at 23', and provided at each side with spring-pockets 24 to receive the

springs 25. 26 designates two friction-blocks 65 slidably mounted within said guide-casing and moved outwardly by the expansion-springs 25. The friction-blocks 26 are provided with projecting lugs 27, working in slots 28 in the back plate 29. The contacting faces of the 70 friction-blocks 26 are inclined and perform the same function as the inclined faces of the guide member in the other constructions.

It will be understood that in Figs. 4, 5, 6, and 7 the draw-bar is omitted from the drawings to diminish the size thereof, but will be readily understood from the showing made.

While I have shown the invention as applied to wooden constructions of cars, it must be understood that it is equally applicable to 80 steel construction.

I desire it to be understood that I do not consider the broad principle of my invention as at all limited to such details of construction as I have shown in the various illustrated 85 forms of my invention.

I claim as my invention—

1. In combination, a draw-bar movably mounted to permit substantial angular movement of the draw-bar under draft stress and 90 a coöperating buffer device carried by the car and constructed to oppose and confine angular movement of the bar, under buffing stress to more restricted limits than its limits of movement under draft. 95
2. In combination, a draw-bar movably mounted so as to be capable of both angular and endwise movement, and a coöperating buffer-guide carried by the car and yieldably mounted to oppose angular movement of the 100 bar under buffing stress.
3. In combination, a draw-bar movably mounted so as to be capable of both endwise and lateral movements, and a coöperating buffer-guide provided with surfaces inclined 105 relatively to the longitudinal axis of the draw-bar and relatively to each other and adapted to coöperate with a part upon the draw-bar.
4. In combination, a draw-bar movably mounted so as to be capable of both angular 110 and endwise movement, and a yieldably-mounted coöperating buffer-guide carried by the car having oppositely-inclined faces adapted to coöperate with the horn of the draw-bar. 115
5. In combination, a draw-bar movably mounted so as to be capable of angular movement, and a coöperating buffer mechanism mounted upon the car and adapted to be brought into functional operation by buffing stress upon the draw-bar and operating to oppose angular movement of the draw-bar under such buffing stress. 120
6. In combination, a draw-bar movably mounted so as to be capable of both angular 125 and endwise movement, a yielding buffer mechanism operating to resist endwise movement of the draw-bar, and an auxiliary buffer

mechanism operating to oppose angular movement of the bar under buffer stress.

7. In combination, a draw-bar movably mounted so as to be capable of both angular and endwise movement, a main yielding buffer mechanism operating to resist endwise movement of the draw-bar and an auxiliary yield-

ing buffer mechanism operating independently of the main buffer mechanism.

GEORGE H. FORSYTH.
